UNITED STATES PATENT OFFICE

1,971,488

HYDROCARBON FUEL BURNING SYSTEM
AND APPARATUSJulius J. Jorgensen, Detroit, Mich., assignor to
Kelvinator Corporation, Detroit, Mich., a cor-
poration of Michigan

Application April 26, 1933, Serial No. 668,001

15 Claims. (Cl. 158—2)

The present invention relates to fuel burning apparatus and more particularly to that type of apparatus which is insertable and withdrawable from a furnace as a unitary structure.

5 One of the objects of the present invention is to provide a swinging pedestal which is capable of supporting the fuel burner removed from the furnace and which is provided with flexible fuel line connections which permit the swinging of 10 the fuel burner on the pedestal toward and away from the furnace.

In accordance with the present invention the fuel burning apparatus is mounted for swinging movement with a bracket and a further object 15 of the present invention is to detachably lock the bracket on its supporting base.

Furthermore, in accordance with the present invention, two fuel lines are provided and a still further object of the present invention is to provide a fitting in which a fuel pipe of one fuel line extends through the flexible connections of the other fuel line and to construct and arrange the parts of the fitting so that the joint between the couplings and between the couplings and the 25 pipe can be simultaneously tightened by a single device.

Another object is to support the fuel burning apparatus on the bracket for limited vertical pivotal movement so that the apparatus can be 30 tilted for insertion into the furnace.

Further objects and advantages will be apparent from the following disclosure, reference being had to the accompanying drawings wherein a preferred form of embodiment of the present 35 invention is clearly shown:

In the drawings:

Fig. 1 is a front view of a furnace showing the present improvement applied thereto;

Fig. 2 is a side view of the fuel burning apparatus showing the burner part of the same inserted in a furnace, the front wall of the furnace being shown in section;

Fig. 3 is a view similar to Fig. 2 except that the burner is shown in a tilted position which 45 position it assumes when it is being inserted or withdrawn from the furnace;

Fig. 4 is a front view of the pedestal which supports a burning apparatus, part of the pedestal being shown in longitudinal cross section;

50 Fig. 5 is a longitudinal sectional view of the fitting for the fuel lines;

Fig. 6 is a sectional view of the pedestal taken on line 6—6 of Fig. 4;

Fig. 7 is a fragmentary view looking in the 55 direction of arrow 7 of Fig. 4; and

Fig. 8 is a fragmentary sectional view taken on line 8—8 of Fig. 4.

Referring to the drawings in general, there is shown a furnace 20, the front wall 21 of which is provided with an opening 22 for receiving the burner part of the fuel burning apparatus 24 (see Figs. 2 and 3). The fuel burning apparatus includes supporting base 25 which carries a motor 26 which drives a fan inclosed within a housing 27 and a rotary fuel burner inclosed within the casing 28. An upwardly extending flange 30 of the base 25 carries a cover 31 of suitable heat resisting material such as asbestos which is arranged to close the opening 22 in the furnace when the apparatus is in position as shown in Fig. 2.

It is desirable that the enlarged head portion of the burner 28 be disposed at a lower level and therefore the burning apparatus is adjacent the sill 32 of the door opening. The fuel burning apparatus is mounted for swinging movement on a pedestal indicated generally as 34 so that the burner may be swung to and away from the furnace and may be swung to insert and withdraw the same from the furnace. In order that the head portion 28 of the burner can clear the bottom sill, the apparatus as a unit can be tilted as shown in Fig. 3.

Referring specifically to the drawings, the pedestal 34 includes a flat plate 36 which rests upon the floor. The base of the pedestal in the form of an upright post or pipe 37 is carried by a dome 38 which in turn is suitably secured to the plate 36. This dome is open as at 39 which opening is covered by a cover plate 40. The electric and fuel lines for the burning apparatus extend into the dome 38 through the opening 39. A collar 42 is adjustably secured on the post 37 by set screws 43. A bracket 45 is swingingly supported on the post 37 and includes a sleeve 46 which telescopes with the post 37 and rests in an under cut portion of the collar 42. The bracket 45 includes a horizontally extending arm 47 on the outer end of which the burning apparatus 24 is carried. The outer end of the arm 47 forms a sleeve 48, the opening 49 in which is circular at the bottom 50 but oblong at the top 51. Depending from the base 25 of the burning apparatus 24 is a post 53 which extends within the opening 49 in the sleeve 48 and upon which the fuel burning apparatus can be oscillated in a horizontal plane and which permits a limited pivotal movement of the burning apparatus in a vertical plane. Stops, which are spaced from one another and one of which is shown at 54, depend from the base 25 and are 55

disposed on opposite sides of an ear 55 formed integrally with sleeve 48. These stops 54 are spaced such distances from the ear as to permit a limited oscillation of the burning apparatus. The opposite walls of the sleeve 48 limit the extent of tilting movement of the burning apparatus as shown in Figs. 2 and 3. A washer 56 is held in place by a screw 57 in the bottom of the post to prevent the promiscuous removal of the burning apparatus from the pedestal. The weight of the fuel burning apparatus to the right of post 53, as viewed in Figs. 2 and 3, is greater than that part to the left of said post; therefore normally the fuel burning apparatus tends to assume the position shown in Fig. 2. However, by pushing downwardly on the motor 26, the fuel burning apparatus 24 can be tilted to the position shown in Fig. 3 so that the head, at the extreme right end thereof, clears the bottom sill 32 of the furnace 20. 10

20 In the particular type of fuel burning apparatus herein shown two fuel lines are connected therewith; one for supplying gas to the burner for pilot purposes and the other for supplying oil. These two fuel lines 60 and 61 and an electrical 25 conduit 62, for supplying current to the electric motor 26, extend into the dome 38 through the opening 39 and from the dome pass upwardly through the post 37, sleeve 46, between the flanges 64 of the arm 47 and from there lead to the proper 30 mechanism of the fuel burning apparatus.

In order that the fuel burning apparatus 24 can be swung on the pedestal, these fuel lines and the electrical connection must be capable of yielding movement. The electrical conduit 62 is 35 formed of flexible material for this purpose and suitable flexible connections are provided in each of the fuel lines in the pedestal. Referring specifically to Figs. 4 and 5, I have illustrated a fitting 66 for the flexibility of the oil and gas lines. 40 This fitting 66 includes a coupling 67 which is connected with an inlet pipe 68. This inlet pipe is connected by a coupling 69 with the flexible fuel line 61. Preferably this fuel line 61 within the dome is made of thin wall copper tubing. A coupling 70 having a shank portion 71 telescopes with the upper part of coupling 67 and the extreme upper part of coupling 67 is recessed and the shank portion 71 is undercut to provide a stuffing box containing the packing 72. The coupling 70 50 is journalled for oscillation in coupling 67 and the upper end forms an extension 73 which is connected by a coupling 74 with the flexible oil line 75. Oil flows through the fuel line 61, leading into the dome 38, through pipe 68, couplings 67, 55 70 and fuel line 75 direct to the fuel burner. When the bracket 47 is swung, it carries with it the pipe 75 which in turn causes the rotation of the coupling 70 in the coupling 67.

Gas for pilot purposes is delivered to the pipe 60 60 extending within the dome 38 which pipe is connected with an upright pipe 77 disposed within the post 37. This pipe is held in position by a bracket 78. A pipe 79 extends longitudinally through the couplings 70 and 67 but is spaced 65 therefrom so as to provide a passage 80 for the flow of oil thereabout. A slip connection is provided between the pipe 79 and pipe 77 whereby the pipe 79 may be extended longitudinally of the pipe 77. In order to prevent the escape of gas 70 at this slip connection, a packing 82 is provided which is pressed against the interior surface of pipe 79 by a hollow bolt 83 having a screw slot 84 for turning the same. By screwing the bolt 83 downwardly, the packing 82 is pressed against 75 the interior surface of the pipe 79. Thus the pipe

79 can be slid longitudinally of the pipe 77 without the leakage of gas at this joint.

A groove is formed in the pipe 79 which receives a split ring 85 which forms a shoulder for a packing gland 86. The lower part of the coupling 67 is recessed to provide a stuffing box containing the packing 87 which tightly embraces the pipe 79. Thus it will be seen that when the coupling 67 is forced downwardly the packing will be pressed tightly against the exterior of the pipe 79 to prevent the escape of oil at this joint. The upper part of coupling 70 is recessed and contains packing 89 which is compressed by a packing gland 90 to prevent the escape of oil at this joint. The upper part of pipe 79 is threaded and receives a nut 91. This nut when screwed downwardly forces the gland 90 downwardly to compress the packing 89 against the exterior of the pipe 79. The tightening of nut 91 also causes the packing 89 to force the coupling 70 downwardly so as to seal the joint of the couplings 70 and 67 and also forces the coupling 67 downwardly to press the packing 87 against the exterior of pipe 79. An elbow coupling 92 is threaded on the upper end of the pipe 79 and is connected with the gas pipe 93 and the upper end of this coupling 92 is closed by a plug 94. A screw 95 is threaded in an extension 96 of the coupling 92 and is utilized for locking the nut 91 in position. When the bracket 45 is swung, the pipe 93 is carried with it causing the rotation of the pipe 79 with the coupling 70. By removing the plug 94 from the coupling 92 a long shank screw driver can be inserted into the pipe 79 for engagement with the screw slot 84 of bolt 83 for tightening the packing 82. The pipe 93 is connected by a swivel coupling 98 with the pipe 99 which leads to the pilot burner. This coupling 98 permits the tilting of the fuel burning apparatus to the position shown in Fig. 3 without bending the pipe connections between the burner and the coupling 92.

By virtue of the present pedestal construction, the burner may be universally used in connection with various types of furnaces. The height of the pedestal can be adjusted to coincide with the height of the fuel door opening of the furnace. By raising and lowering the collar 42 on the post 37, the height of the bracket 47 can be varied to suit the particular type of furnace. The flexible oil pipe 61 in the dome 38 permits the raising and lowering of the connection 66 and the slip connection between the pipes 77 and 79 permits the longitudinal extension of the gas pipe line. A bracket 101 connected with the interior of the post 37 guides the pipe 77 and likewise the connection 66. Access may be had to the interior of the bracket 45 through the top through an opening which is normally closed by a plate 102 held in position by screws 103.

Means are provided for yieldingly holding the bracket 45 in its position in which the fuel burner is disposed within the furnace or when the bracket is swung outwardly from the furnace 90°. This means comprises a pin 105 extending downwardly into the collar 42 and notches one of which is shown as 106, the other notch being removed 90° to the left of view in Fig. 4. The pin 105 resting within the notch 106 normally prevents the turning of the bracket 45, however, the bracket may be swung causing the lower part of the sleeve to ride on top of the pin 105 but as soon as the lower edge of the notch 106 comes in contact with the pin the bracket will center itself with respect to the apex of the notch 106. In order to prevent inadvertent swinging of the

burner while it is in the furnace, a lock is provided for locking the bracket 45 against rotation. A lug 106^a is formed on the collar 42 which lug receives an L shaped bolt 107 held in place by 5 a pin 108 through the lower part thereof. This lug 106^a forms a hinge for the bolt 107 so that the bolt may be swung between two lugs 109 formed on the sleeve 46. The outer end of the bolt 107 is threaded to receive a wing nut 110

10 which when tightened in the position shown in Fig. 7, locks the sleeve 46 with the collar 42 so as to prevent the turning of the bracket 45.

It will be noted that the pedestal 34 is fixed at the far left hand corner of the plate 36 so as 15 to provide a wide base to the left and forward of the pedestal 34 to prevent the tilting of the entire apparatus either when it is in its position in the furnace or removed 90° therefrom.

Thus it is apparent from the foregoing that I 20 have provided a pedestal which will permit the swinging of the fuel burner into and out of the furnace in which the height of the pedestal is also adjustable for universal use for various types of furnaces.

25 While the form of embodiment of the present invention as herein disclosed constitutes a preferred form, it is to be understood that other forms might be adopted, all coming within the scope of the claims which follow.

30 What I claim as my invention is:

1. A swinging pedestal for a fuel burning apparatus comprising in combination, a hollow supporting post, a bracket for carrying the fuel burning apparatus swingingly supported by the 35 post, a fuel line extending longitudinally through the post for supplying fuel to the burning apparatus, said fuel line including a coupling having a stationary part carried by the post and a movable part carried for swinging movement by the bracket, and a packing at the joint of said parts of the coupling.

2. A swinging pedestal for a fuel burning apparatus comprising in combination, a hollow supporting post, a bracket for carrying the fuel burning apparatus swingingly supported by the post, and movable longitudinally of the post for adjusting the height thereof, means for adjustably limiting the downward movement of the bracket, a fuel line extending longitudinally through the 45 post for supplying fuel to the burning apparatus, said fuel line including a coupling having a stationary part carried by the post and a movable part carried for swinging movement by the bracket, and a packing at the joint of said parts of the coupling.

3. A swinging pedestal for a fuel burning apparatus comprising in combination, a hollow supporting post, a bracket for carrying the fuel burning apparatus, said bracket including a sleeve telescoping the post, means on the post for limiting the downward movement of the bracket, a fuel line extending longitudinally through the post for supplying fuel to the burning apparatus, said fuel line including a coupling having a stationary part carried by the post and a movable part carried for swinging movement by the bracket, and a packing at the joint of said parts of the coupling.

4. A swinging pedestal for a fuel burning apparatus comprising in combination, a hollow supporting post, a bracket for carrying the fuel burning apparatus, said bracket including a sleeve telescoping the post, a collar adjustably fixed to said post and forming a stop for adjustably regulating the height of the bracket, a fuel line

extending longitudinally through the post for supplying fuel to the burning apparatus, said fuel line including a coupling having a stationary part carried by the post and a movable part carried for swinging movement by the bracket, and a packing at the joint of said parts of the coupling.

5. A swinging pedestal for a fuel burning apparatus comprising in combination, a hollow supporting post, a bracket for carrying the fuel burning apparatus, said bracket including a sleeve

80

telescoping the post, a collar adjustably fixed to said post and forming a stop for adjustably regulating the height of the bracket, a fuel line extending longitudinally through the post for supplying fuel to the burning apparatus, said fuel

85

line including a coupling having a stationary part carried by the post and a movable part carried for swinging movement by the bracket, and a packing at the joint of said parts of the coupling, and latching means associated with the post and

90

bracket for detachably latching said post and bracket with one another.

95

6. A swinging pedestal for a fuel burning apparatus comprising in combination, a hollow supporting post, a bracket for carrying the fuel burning apparatus swingingly supported by the post, a fuel line extending longitudinally through the post, and latching means associated with the post and bracket for detachably latching said post and

100

bracket together.

105

7. A swinging pedestal for a fuel burning apparatus comprising in combination, a hollow supporting post, a bracket for carrying the fuel burning apparatus swingingly supported by the post and movable longitudinally of the post for adjusting the height thereof, means for adjustably limiting the downward movement of the bracket, and latching means associated with the bracket and the first mentioned means for detachably latching said post and bracket together.

110

8. A swinging pedestal for a fuel burning apparatus comprising in combination, a hollow supporting post, a bracket for carrying the fuel burning apparatus, said bracket including a sleeve telescoping the post, a collar adjustably fixed to said post forming a stop for adjustably regulating the height of the bracket, and latching means associated with the collar and sleeve for detachably latching said post and bracket together.

115

9. A swinging pedestal for a fuel burning apparatus comprising in combination, a supporting base, a bracket for carrying the fuel burning apparatus swingingly supported by the base, a fuel line for the apparatus including a coupling carried by the base, a second coupling having a fluid tight joint with the first and mounted for swinging movement with the bracket, a pipe journaled for oscillation in said couplings and adapted to deliver fuel to the apparatus, and means for sealing the joints of the pipe and couplings.

120

10. A swinging pedestal for a fuel burning apparatus comprising in combination, a supporting base, a bracket for carrying the fuel burning apparatus swingingly supported by the base, a fuel line for the apparatus including a coupling carried by the base, a second coupling telescoping with the first, said second fitting having a fluid tight joint with the first and mounted for swinging movement with the bracket, a pipe journaled for oscillation in said couplings and adapted to deliver fuel to the apparatus, and means for sealing the joints of the pipe and couplings.

125

11. A swinging pedestal for a fuel burning apparatus comprising in combination, a support-
